E. E. SLICK,
CAR TRUCK,
APPLICATION FILED JUNE 20, 1916.

1,195,112.

Patented Aug. 15, 1916.

WITNESS

Elmer Seaver.

BY

Edwin E. Slick.
Geo. E. Thackray
ATTORNEY

UNITED STATES PATENT OFFICE.

EDWIN E. SLICK, OF WESTMONT BOROUGH, PENNSYLVANIA.

CAR-TRUCK.

1,195,112.

Specification of Letters Patent. Patented Aug. 15, 1916.

Application filed June 20, 1916. Serial No. 104,662.

To all whom it may concern:

Be it known that I, EDWIN E. SLICK, a citizen of the United States, residing in the borough of Westmont, in the county of Cambria and State of Pennsylvania, (whose post office address is Johnstown, Pennsylvania,) have invented certain new and useful Improvements in Car-Trucks; and I do hereby declare the following to be a full, clear, and 10 exact description of the invention, such as will enable others skilled in the art to which it appertains to make and use the same.

My invention relates to improvements in car trucks with particular reference to those 15 which are used for railroad cars and are particularly adapted for use in connection with the heavy types of freight cars.

My invention also relates particularly to the construction and arrangement of the side 20 frames for car trucks which I make of wrought or rolled steel, thereby providing a material which is best adapted to withstand the loads, shocks and impacts to which it is subjected in severe service. By constructing my truck frame of rolled steel, I 25 provide material which, by its method of manufacture, inspection and tests, is known to be solid and integral throughout each part of its section and which may be of desired 30 qualities and of any strength required, so that each part is best adapted to withstand the stresses to which it will be subjected in use. I also prefer to secure the parts together by means of rivets which are upset 35 when cold, in the holes provided therefor, and the heads, formed, at the same time, by cold upsetting. This method of securing the parts together works or flows the rivets to 40 stresses and strains beyond their elastic limit when cold, and pinches and clamps the attached parts very firmly together so that no stresses less than the increased elastic limit of the material due to said cold working, can affect these parts in use. By this 45 means I provide with the same amount of material, a much stronger junction than can be accomplished by means of hot driven rivets which are upset by stresses very much less than cold driven ones in the ratio of 50 about 1 to 20.

I preferably construct the lower member of my truck frame of steel, rolled or pressed into trough-sections, the intermediate portion of which is spaced apart 55 from the upper member a considerable dis-

tance and with integral inclined portions extending upwardly toward the upper member and thence extending substantially horizontal at each end, thereby forming portions with broad flat lower surfaces comprising the web portions of the trough-section which are well adapted to rest upon the journal boxes. I prefer to place this lower member with its flanges extending upwardly and secured to side plates by means of cold-driven rivets, as heretofore described. 60 I also prefer to arrange the upper member which is of section similar to that of the lower member, with its flanges extending upwardly and secured to the side plates by 65 means of cold-driven rivets. I provide side plates on each side of my truck frame, each of said plates being integral and provided with a large central opening adapted to receive the bolster, these plates being secured 70 to the side flanges of the top and bottom members by cold riveting. Around the central opening I provide a member of bent angle section to conform to the outline desired and secured to the side plates and 75 the lower and the upper member by rivets. Attached to the upper portions of the insides of said bent angle members and side plates, I provide trough-shape portions extending a short distance inwardly of the opening 80 and adapted to form guides for the bolster, the lower part of the opening being large enough to admit the bolster with integral 85 guide lugs thereon, which, after being inserted through the lower part of the opening, is moved upwardly and the springs set 90 below it in final position. I also provide seat plates for the bolster springs, and also other members corresponding to spring planks, which in this case are shown as 95 angles, extending from the truck frame on one side of the car to that on the other, to square the trucks and hold the frames together. I also provide the usual bolts for 100 securing the journal boxes in place, holes being provided for this purpose through the end portions of my truck frame. I also secure to the truck frame, brake hanger carriers which are also formed of steel and securely riveted to the frame. 105

Having thus given a general description of my invention, I will now refer to the annexed sheet of drawings in which like characters refer to like parts.

Figure 1 is a side elevation of a railway 110

car truck, provided with a side frame embodying my invention; Fig. 2 is a vertical longitudinal sectional elevation of my improved side frame; Fig. 3 is a top plan view of the side frame; Fig. 4 is a vertical transverse sectional elevation taken on the line IV—IV of Fig. 2, and Fig. 5 is a sectional elevation taken on the line V—V of Fig. 2 drawn on an enlarged scale.

- 5 Referring now to the various characters of reference on the drawings: 1 represents the upper member or arch bar of my side frame which is formed of trough or channel shape, rolled or pressed as desired, the 10 flanges of the same being shown as projecting upwardly; the inverted arch bar is indicated as 2, which is of section similar to the upper arch bar and is also arranged with its flanges projecting upwardly, the lower 15 portion of this arch bar extending substantially horizontally, spaced apart from the upper member and provided with the diagonal or inclined portions 3, as illustrated, and with the horizontally-extending end 20 portions 4, as shown; 5 and 6 are each the integral side web plates of which there are two to each truck frame, one on each side of the arch bars and secured thereto by cold-driven rivets, as shown. 25 Each of these side web plates is provided with a central opening, as shown, to receive the bolster and are reinforced around their edges adjacent to said opening by means of the bent angle reinforcement or truck columns 13, one of these being on each side of 30 the side frame. At the ends of the truck I provide the holes 7 and 8 in the web portion of the upper arch bar 1, and the holes 9 and 10 in the smaller portion of the lower bar, 35 the flat ends of the web of the inverted arch bar being adapted to receive the journal box bolts 11 and 12, and in this connection it should be noted that these parts are so arranged that all the journal-box bolts are of 40 the same length and size, which conduces to ease of construction and repair. The bolster spring seat is composed of a steel plate 14, which is mounted on and riveted to the lower portion of the truck column or reinforcing angles 13, as shown. The spring 45 planks are illustrated in this case as composed of two angles 15, which are riveted to the column guides, as shown, and extend from one side truck frame to the companion 50 frame on the other side of the truck for the purpose of squaring and holding the two portions together. Between the inwardly projecting legs of the angles 15, I place and secure a filler plate 16 for the purpose of 55 forming a level surface to receive the bottom spring plate or the bolster springs 17, which latter are illustrated as of the usual helical type. The bolster 18 may be of any 60 usual type provided with guides at its end 65 portions, adapted to fit around the column

guides 19. The column guides 19 are formed, as illustrated, of shallow trough-shape plates secured by rivets countersunk on the outside to the member 20, which member 20 is of trough-shape with its flanges extending inwardly between the opposing pair of truck columns and side plates and riveted thereto, as illustrated. The portion 19 is adapted to serve as a wearing plate and can be easily replaced at any time on account of 75 the wear due to the motion of the bolster against the same. I also provide a brake hanger carrier which is illustrated as 21, composed of a bar of steel of shape shown, riveted to the truck frame as particularly 80 illustrated in Fig. 5, the outwardly projecting portion being adapted to receive a brake hanger. I also provide pedestal tie-bar brackets 22 secured to the diagonal or inclined webs of the inverted arch bar, as 85 illustrated, and the pedestal-tie bars 23, are secured to the brackets by rivets and to the journal boxes by means of the bolts 11 and 12, as customary.

As illustrated in Fig. 4, I prefer to cut 90 away the outwardly extending portions of the vertical legs of the truck columns or reinforcing angles, making them of tapering form, smaller at the top than at the bottom, but I may also make them parallel, if 95 desired.

It should be noted that I prefer to arrange the inverted arch bar of trough or channel form with its flanges projecting upwardly and secured to the side plates, thereby forming a smooth finished surface on the lower side of the frame and on the outwardly extending end portions thereof, thus providing a smooth finish and substantial bearings on the journal boxes. I also prefer 100 to have the flanges of the upper arch bar, which is also of trough section, extend upwardly for ease of riveting the same in place, as the riveting machine can easily take hold of the rivets in these outstanding 105 portions. The riveting of the lower arch bar can also be easily accomplished before the upper one is put into place, as in this case the riveting machine can be inserted in the opening between the side plates. 110

It should also be noted that openings of substantially triangular shape with rounded corners are provided on each side of the bolster opening, for the purpose of lightening the construction and affording means of 115 access to the interior for the purpose of construction, inspection or repair.

Although I have described and illustrated my invention in considerable detail, I do not wish to be limited to the exact and specific 125 details thereof, as shown and described, but may use such modifications in, substitutions for, or equivalents thereof, as are embraced within the scope of my invention, or as pointed out in the claims.

Having thus described my invention, what I claim and desire to secure by Letters Patent is:—

1. A truck frame comprising an upper arch bar and a lower arch bar, both of trough section, with their flanges projecting upwardly, spaced apart at their intermediate portions and closer together at their end portions, and an integral side plate secured on each side to the flanges of said arch bars. 5
2. A truck frame comprising an upper arch bar and a lower arch bar of trough section, the intermediate portion of the lower arch bar being spaced apart from the upper arch bar and provided with inclined portions extending upwardly toward the upper arch bar, and with horizontal end portions adjacent thereto, an integral side plate secured on each side of the frame to the upwardly projecting flanges of the arch bars, said side plates being each provided with a central opening and around which is secured an integral bent angle forming 15 a column guides and support for the spring seat. 20
3. A truck frame comprising an upper arch bar and a lower arch bar of channel section with their flanges extending upwardly, an integral side plate secured on each side of the frame to the flanges aforesaid, a bolster opening in said side plates, a column guide and a spring-seat support comprising an integral bent angle having a lower seat portion and two upwardly-extending portions secured to each of the side plates, bolster guides secured to the upper portions of said angles and side plates and projecting inwardly therefrom. 25
4. A truck frame comprising an upper arch bar and a lower arch bar of trough section, with their flanges projecting upwardly, an integral side plate, having a bolster opening, secured on each side of said frame to the flanges aforesaid, bolster guides comprising channel sections secured to and between the upper portions of said side plates and projecting inwardly of the opening. 40
5. A truck frame comprising a pair of upper and lower arch bars, a pair of side plates secured to the opposite sides thereof and provided with a bolster opening therein, a bolster guide comprising a trough section secured to and between the upper portions of the side plates, projecting within the bolster opening and provided with a reinforcing plate of shallow channel form. 55
6. A truck frame provided with top and bottom arch bars of channel section with their flanges extending upwardly, the lower arch bar having portions inclining upwardly toward the upper member, and horizontal portions approximately parallel and adjacent to said upper member and means 60 for securing said bars together by their flanges. 70
7. A truck side frame comprising flanged top and bottom members spaced apart at the center and adjacent at their end portions, the ends of both members being secured on the upper portions of the journal boxes, said members being connected together by integral side plates secured to their flanges. 75
8. A truck side frame comprising flanged top and bottom members spaced apart at the center and adjacent at their end portions, the ends of both members being secured on the tops of the journal boxes, said members being connected together by integral side plates secured to their flanges, the side plates being provided with a bolster opening and reinforced around the side and bottom thereof by integral bent angles secured thereto. 80
9. A truck side frame comprising a top member and a bottom member of trough section, integral side plates secured to the flanges on each side thereof, said side plates being provided with a bolster opening and with bolster guides secured between said plates at the upper portion of said bolster opening and projecting inwardly thereof. 85
10. A truck frame of the character described, provided with top and bottom arch-bar members, an integral side plate secured to each side thereof, a bolster opening in said side plates and a reinforcing flange member secured to each of said plates around the sides and bottom of said bolster opening. 90
11. A truck frame of the character described, provided with top and bottom arch-bar members, an integral side plate secured to each side thereof, a bolster opening in said side plates, reinforcing flanges on said plates around the sides and bottom of said bolster opening, and column guides secured to said plates and projecting inwardly in the upper portion of the opening. 95
12. A truck frame comprising an upper arch bar and a lower arch bar, integral side plates secured thereto, a brake hanger comprising an approximately cylindrical portion passing through said side plates and secured thereto, having an inwardly projecting portion adapted to receive a brake hanger. 110
13. A truck side frame comprising an upper arch bar and a lower arch bar, both of channel or trough section, with their flanges projecting upwardly and spaced apart at their intermediate portions, the lower arch bar inclining upwardly from its lower portion toward the upper arch bar, the ends of the lower arch bar extending horizontally adjacent to the ends of the upper arch bar, an integral side plate secured to each side of said bars through the flanges thereof, a pedestal tie-bar secured to 120
14. A truck side frame comprising an upper arch bar and a lower arch bar, both of channel or trough section, with their flanges projecting upwardly and spaced apart at their intermediate portions, the lower arch bar inclining upwardly from its lower portion toward the upper arch bar, the ends of the lower arch bar extending horizontally adjacent to the ends of the upper arch bar, an integral side plate secured to each side of said bars through the flanges thereof, a pedestal tie-bar secured to 125
15. A truck side frame comprising an upper arch bar and a lower arch bar, both of channel or trough section, with their flanges projecting upwardly and spaced apart at their intermediate portions, the lower arch bar inclining upwardly from its lower portion toward the upper arch bar, the ends of the lower arch bar extending horizontally adjacent to the ends of the upper arch bar, an integral side plate secured to each side of said bars through the flanges thereof, a pedestal tie-bar secured to 130

the inclined portion of the frame and to the lower side of the journal box, journal box seats on the horizontal end portions of said truck frame, bolts passing through said seats and the pedestal tie-bar.

14. A truck frame of the character described comprising an upper and a lower arch bar, side plates secured thereto, a bolster

opening therein, reinforcing angles surrounding the sides and bottom of said opening and secured to said side plates, the outwardly projecting flanges on the vertical portions of said reinforcing member being wider at the bottom than at the top. 10

EDWIN E. SLICK.
